ADVERTISING DISPLAY DEVICE

William Melish Harris, Greenwich, Conn.

Application September 9, 1950, Serial No. 184,033

2 Claims. (Cl. 40—132)

This invention relates to advertising display devices and more particularly to those adapted for use in stores or other business places and which are mounted on and form a so-called "superstructure" for refrigerating cabinets such as are employed for containing frozen food products or other frozen commodities.

An object of the invention is to provide a display device of the above character, adapted to changeably hold pictures or pictorial representations, preferably colored and suitably illuminated, of the various goods contained in the cabinet upon which the display device is mounted, to thus appetizingly and attractively display the goods and invite the purchase thereof. It is another object of the invention to provide means by which the pictorial representations carried by the display device may be readily changed or shifted in position or arranged in suitable juxtaposition to price cards or signs which may also be changeably carried by the display device.

It is still another object of the invention to provide a display device of this character which can be easily and economically fabricated, which can be maintained clean and sanitary in appearance; which can be readily adapted to refrigerating cabinets or other containers of various styles and which will present an attractive and clean-cut appearance.

More particularly, the invention contemplates the provision of a hollow, interiorly illuminated housing, preferably and to a major extent, composed of a shell of translucent plastic sheet material. Said shell carries on its outer face, and attached thereto by adhesion or other means herein described, colored transparencies showing the goods advertised.

The invention also contemplates the provision of novel means by which the illustrations may be held in place on the other face of the shell, and the shell readily mounted on a cabinet or other support.

With the above, and other objects to be herein-after set forth, in view, I have devised the particular arrangement of parts to be described and more particularly pointed out in the claims appended hereto.

In the accompanying drawing, wherein an illustrative embodiment of the invention is disclosed, Fig. 1 is a perspective view of an advertising display device constructed in accordance with the invention, and with a portion of the translucent plastic shell broken away to disclose construction.

Fig. 2 is a vertical sectional view through the

55

proper positioning of the device on a cabinet.

This invention relates to advertising display devices and more particularly to those adapted for use in stores or other business places and which are mounted on and form a so-called "superstructure" for refrigerating cabinets such as are employed for containing frozen food products or other frozen commodities.

The invention is particularly adapted for use in connection with refrigerating cabinets, such as are employed for containing frozen food products, and which are mounted on and form a so-called "superstructure" for the cabinets.

The invention is particularly adapted for use in connection with refrigerating cabinets, such as are employed for containing frozen food products, and which are mounted on and form a so-called "superstructure" for the cabinets.

The invention is particularly adapted for use in connection with refrigerating cabinets, such as are employed for containing frozen food products, and which are mounted on and form a so-called "superstructure" for the cabinets.

Referring to the drawing, 1 indicates the shell of the display device. The shell is preferably composed of plastic material of translucent nature and the same may be made in various shapes and sizes to enable it to be accommodated to various types of refrigerators, cabinets, counters or other supports on which it may be mounted to advertise goods or to display pictorial representations of the goods constituting the contents of the refrigerator or other cabinet on which it may be mounted. In the form shown, the shell 1 is of concavo-convex formation and is provided along its top and side edges with an outwardly bent integral flange 2 which takes under a bent-over flange 3 provided on the edges of a back plate or rear closure member 4 that fits over and normally closes the open back of the shell 1, and carries the interior lighting equipment to be described.

When the shell is fitted on top of a refrigerator or other cabinet, such as a frozen food cabinet for example, to form a superstructure therefor, a sealing gasket 5 of rubber or other material of similar characteristics may be used between the lower edge of the shell 1 and the top of the cabinet.

10 The housing thus formed of the shell 1 and its rear closure plate 4, is interiorly illuminated by means of suitable lighting equipment, such as the fluorescent lamps shown at 7 and 9 which have their sockets supported by the brackets 6 and 10 mounted on and carried by the back plate 4, as clearly shown in Fig. 1. Brackets 6 may also be employed for the support of a lamp starter 8 and the ballast 13 for the lamps may also be mounted on the plate 4.

15 The mounting for the shell and its attached back plate 4 may be had in various ways according to its position and arrangement on the cabinet or other support on which it is to be carried. For attachment to the top portion of a frozen food cabinet, legs 14 may be employed, the same being in the form of channel-shaped members, attached by the bolts 20 or other fastening means to the plate 4; said legs have portions 15 projecting below the shell, and said projecting portions are provided with mounting holes 21 through which screws or other fastening elements may be passed to attach the device to a cabinet. Spacers 16 are also employed at the lower portions of the legs 14 to facilitate the

20 proper positioning of the device on a cabinet. The mounting thus formed of the shell 1 and its rear closure plate 4, is interiorly illuminated by means of suitable lighting equipment, such as the fluorescent lamps shown at 7 and 9 which have their sockets supported by the brackets 6 and 10 mounted on and carried by the back plate 4, as clearly shown in Fig. 1. Brackets 6 may also be employed for the support of a lamp starter 8 and the ballast 13 for the lamps may also be mounted on the plate 4.

25 The mounting for the shell and its attached back plate 4 may be had in various ways according to its position and arrangement on the cabinet or other support on which it is to be carried. For attachment to the top portion of a frozen food cabinet, legs 14 may be employed, the same being in the form of channel-shaped members, attached by the bolts 20 or other fastening means to the plate 4; said legs have portions 15 projecting below the shell, and said projecting portions are provided with mounting holes 21 through which screws or other fastening elements may be passed to attach the device to a cabinet. Spacers 16 are also employed at the lower portions of the legs 14 to facilitate the proper positioning of the device on a cabinet.

3

A removable, or possibly a hinged, door 11 is provided in the rear plate 4 to permit ready access to the interior of the housing and the lighting equipment contained therein, and ventilating louvers 12 are provided in the upper portion of the plate 4.

It is desirable to provide advertising or illustrative matter on the front face of the translucent shell 1 and such material may be applied thereto in various ways. One satisfactory way of attaching pictures, price cards or other illustrative matter to the shell is by directly adhesively attaching such material to the outer surface of the shell. This may be done by providing the illustrations to be affixed, with a pressure-sensitive adhesive on their backs so that they can be affixed to the face of the shell by merely pressing them firmly against the same. They can also be affixed by the use of pressure-sensitive tape such as the transparent kind commercially known as "Scotch tape." If such illustrations are in the form of colored transparencies, the light penetrating through the plastic shell and through the pictures applied thereto, will provide very attractive effects and will help immeasurably in selling the pictured goods.

The pictures or other advertising matter can be carried by the shell 1 in another way as illustrated in the drawing. Therein, spaced retaining strips 17 of plastic material, and preferably of a material of wholly transparent nature, are shown applied to the outer surface of the shell 1 so that these strips form supports or confining members for pictures, signs or other illustrative matter, such as indicated in dotted lines in Fig. 1 at 19. To enable these retaining strips 17 to stand off from the front surface of the shell 1 and provide space behind them for the edges of the pictures 19, portions of the shell 1 are distorted outwardly as shown at 18, thus forming longitudinally extending spaced ribs on the outer surface of the shell and to which the strips 17, which are wider than such ribs, are adhesively attached.

With the described arrangement, pictures, illustrations, advertising matter or the like may be readily inserted between the strips 17 and confined in place thereby and held flatly against the surface of the shell 1. The maintenance of the pictures in position by the strips permits the pictures to be readily changed around or removed and replaced with others whenever desired. The strips 17, being of transparent nature, are nearly invisible, particularly when illuminated from the rear, and thus the entire area of any card or picture retained by them will be exposed and no portion of it obscured.

When a shell of translucent nature is illuminated from the interior as above described, uniform light over the entire area of the shell will result, and when transparencies are provided on the outer face of the shell, the light penetrating through the same will provide very attractive effects. The changeability of the pictures and advertising matter and the simplicity with which such material may be affixed, shifted or removed, enables the storekeeper to easily and frequently

4

change his illustrations and signs without disturbing the superstructure on its support.

In the embodiment of the invention shown in Fig. 4, the ribs produced by the outwardly distorted portions 18 are eliminated and the strips therein shown at 23 are transversely shaped to provide one or more recesses 24 behind them to thus produce supporting shoulders for the edges of the pictures.

While I have herein described one embodiment of the invention, it is obvious that the same is not to be restricted thereto, but is broad enough to cover all structures coming within the scope of the annexed claims.

What I claim is:

1. A display unit for refrigerating cabinets, comprising a flat metallic plate resting on its lower edge and extending vertically upwardly from the top of a refrigerating cabinet, a translucent plastic shell having an open back defined by a flange attached to the marginal edge of the plate to thereby cause said plate to close the back of the shell, the shell having an open bottom resting on the top of the refrigerating cabinet, legs attached to the plate and having portions extending downwardly behind the refrigerating cabinet for attachment to the back of the cabinet, the plastic shell being formed to provide a closed top, front and sides of a lamp enclosure, lamps attached to the plate within the shell for the projection of light through the shell, and means on the outside of the shell for removably attaching advertising matter thereto.

2. A display unit for refrigerating cabinets, comprising a flat metal plate extending vertically upward from the top of a refrigerating cabinet, a translucent plastic shell having an open back, the edge of said shell being attached to the marginal edge of the plate to thereby cause said plate to close the back of the shell, the shell having a bottom resting on top of the refrigerating cabinet, securing means attached to the plate and having parts extending downwardly behind the refrigerating cabinet for attachment of the plate to the back of the cabinet, the plastic shell being of a shape to provide a closed top, front and sides of a lamp enclosure, lighting means attached to the plate within the shell for the projection of light through the shell, and means on the shell for attaching advertising matter thereto for the illumination of said advertising matter by the lighting means within the shell.

WILLIAM MELISH HARRIS.
